UNITED STATES PATENT OFFICE.

HALBERT B. HALVORSEN, OF CHICAGO, ILLINOIS, ASSIGNOR TO SULLIVAN MACHINERY COMPANY, A CORPORATION OF MASSACHUSETTS.

AIR-LIFT BOOSTER.

1,398,550.

Specification of Letters Patent. Patented Nov. 29, 1921.

Application filed April 11, 1917. Serial No. 161,351.

To all whom it may concern:

Be it known that I, HALBERT B. HALVORSEN, a citizen of the United States, residing at Chicago, in the county of Cook and State 5 of Illinois, have invented certain new and useful Improvements in Air-Lift Boosters, of which the following is a full, clear, and exact specification.

My invention relates to air lift boosters.

10 It has for its object to guide and control in an improved manner the movement of the valve and valve controlling float used in such a booster and thereby overcome the objectionable effects upon the valve and float 15 of surging of the water within the booster. More specifically, my invention has for its object to provide an improved booster equipped with improved means whereby, despite this surging, the float is correctly 20 guided, and improved coöperating means whereby the water is prevented from surging up into the float in such a manner as to interfere with its operation. These and other objects and advantages of my improvement 25 will, however, hereinafter more fully appear.

In the accompanying drawings, I have shown for purposes of illustration, one embodiment which my invention may assume 30 in practice.

In these drawings,—

Figure 1 shows one form of air lift system with which my improvement may be used, the booster being shown in section. 35 Fig. 2 is a side elevation of the booster tank, the same being broken away to show the float and valve mechanism.

Fig. 3 is a detail view of the float mechanism.

40 Fig. 4 is a sectional view taken on line 4—4 of Fig. 3.

Fig. 5 is a sectional view of a modified form of connection between the float guide and the valve casing.

45 In the illustrative embodiment, I have shown an air lift system of a usual type including a compressor 1, which may be of any known construction, delivering air into a receiver 2, which in turn delivers air to a 50 down pipe 3 leading to the foot-piece 4 of the air lift pump located in the well. By this pump the air is mixed with the liquid in the well in such a manner as to cause the latter to flow upward through an outer pipe 5 of 55 larger diameter, into the booster casing 6.

Therein, through the action of an interposed umbrella top 7, the air and liquid are separated, the air then acting upon the surface of the liquid in a well known manner to force the same beneath a baffle plate 8 and 60 propel the same upward through the discharge pipe 9 to the line. As usual, in such systems, the excess air escapes through a relief or exhaust valve 10, rigidly connected to and controlled by a float 11 herein of the 65 diving bell type, and is conducted through a pipe 12 to the atmosphere or, as shown, back to the intake of the compressor.

In the use of such a system, it has been found that when surging is encountered in 70 the booster casing 6, the action of the valve 10 is interfered with, the surging often acting upon the float 11 in such a manner as to force the same out of line with the valve, and as a result cause bending of the valve 75 rod and binding and sticking of the valve. In my improved construction, however, it will be noted that the lower end of the valve rod 13, on which the float 11 is carried, extends through the bottom of a rigid guide or 80 yoke 14 of any suitable form, herein illustrated as of substantially U-shape, attached at its upper end to the top of the booster casing, the lower end of the valve rod 13 preferably being slidable through a bushing 85 15 threaded in the bottom of this yoke. Thus, it will be noted that the float is mounted in a rigid guide and that the float and valve are maintained in axial alinement with the valve casing despite any surging in 90 the booster casing. In a preferred form, the upper ends of this yoke 14 are connected to the valve casing 16, and this valve casing is itself disposed over an opening 17 in the top of the booster casing and removably attached to the latter, as by means of bolts 18. Thus, it will be noted that it is made possible to lift out the float and yoke bodily from the booster casing by simply removing the bolts 18 which clamp the valve casing 16 95 thereto. It will also be noted that upon the bottom of the yoke 14 and adjacent the open lower end of the float 11, I have shown herein improved means in the form of a circular plate 19 which acts in such a manner as to 100 prevent the liquid from surging into the open bottom of the diving bell float shown and at the same time is bodily removable with the valve and float guiding yoke 14.

Obviously, in the use of my improvement, 110

the air lift system will operate in the usual manner, the valve 10 being so automatically controlled by the float 11 as to maintain the pressure in the booster needed to propel the liquid through the line. In the use of my improved device, however, it has been found that due to the provision of the yoke and the rigid mounting of the float resulting therefrom, all difficulty with bending of the valve rod, and the resultant disarrangement in the operation of the valve and the control by the latter of the pressure, is effectively prevented. It has also been found that due to the provision of the plate 19 the flow of liquid into the open bottom of the float has been cut down in such a manner as to prevent the surging of a large quantity of water into the float and such bending of the valve rod or float as may result therefrom.

Obviously, my improvement may be used, if desired, with any suitable means for controlling the buoyancy of the float, as for instance a spring mechanism acting upon the upper end of the valve rod. This mechanism, however, is the invention of one John Oliphant, and as the same *per se* does not enter into the present invention, it need not be specifically described. It will also be obvious that with the improved means for guiding the float or preventing the surging of the liquid therein, any suitable valve mechanism may be used, if desired, and that the float itself may be made adjustable relative to the valve rod, as shown, in order to adjust the same relative to the valve. It will also be noted that, as shown in Fig. 5, instead of having the yoke 14 directly attached to the valve casing 16, this yoke may be connected, if desired, to an intermediate plate 20 removably attached to the top of the booster casing by bolts 21 and threaded at 22 to receive a correspondingly threaded and tapered extension or collar 23 on the lower end of the valve casing. Obviously, with such a construction, the entire float and guide may still be withdrawn through the opening in the top of the booster casing, and the valve casing may be separately removed when desired.

While I have in this application specifically described two embodiments which my invention may assume in practice, it is to be understood that the same are used for purposes of illustration, and that the invention may be modified and assume various other forms without departing from its spirit, it being my intention to include all such modifications within the scope of the appended claims.

What I claim as new and desire to secure by Letters Patent is:

1. In combination, a booster casing having means for the admission of a mixture of gaseous pumping fluid and liquid thereto

and for the discharge of the latter therefrom, and means for maintaining a substantially constant liquid level in said casing comprising a relief valve, a float connected to and movable therewith, and float guiding means carried by the top of the booster casing.

2. In combination, a booster casing having means for the admission of a mixture of gaseous pumping fluid and liquid thereto, and for the discharge of the latter therefrom, and means for maintaining a substantially constant liquid level in said casing comprising a relief valve, a float connected to and movable therewith, and valve and float guiding means carried by the top of the booster casing.

3. In combination, a booster casing having means for the admission thereto of a mixture of a gas and a liquid, discharge means for one of said fluids, and means for maintaining a substantially constant liquid level in said casing comprising an opening in said casing, a valve casing covering said opening, a valve controlling the admission of fluid to said valve casing, a float controlling said valve and connected thereto, and float guiding means connected to said valve casing and removable therewith through said orifice.

4. In combination, a booster casing having means for the admission thereto of a mixture of a gas and a liquid, discharge means for one of said fluids, and means for maintaining a substantially constant liquid level in said casing comprising an opening in said casing, a valve casing covering said opening, a valve controlling the admission of fluid to said valve casing and its discharge therefrom, a float controlling said valve and connected coaxially thereto, and float guiding means connected to said casing and removable therewith through said orifice.

5. In combination, in an air lift mechanism, a booster casing having inlet and discharge pipes therein, and means for maintaining a substantially constant liquid level in said booster consisting of a relief valve, a valve rod connected thereto and extending into said casing, a float carried on said valve rod, and rod guiding means depending from the top of the booster casing.

6. In combination, in an air lift booster, a booster casing having inlet and discharge pipes therein, and an opening in its top, a relief valve, a rod connected thereto, a diving bell float through which said rod passes and to which said rod is attached at the upper end thereof, and means for maintaining the lower end of said diving bell float concentric with said rod comprising a brace of less width than the diameter of the mouth of said bell and extending between said rod and the side of said bell at a point below the top thereof.

7. In an air lift booster, a booster casing having inlet and discharge pipes therein, and means effective to maintain a substantially constant liquid level in said booster 5 consisting of a removable valve casing disposed over an opening in said booster casing, a valve movable in said casing, a rod connected to said valve and extending into said booster casing, a float carried on the lower end of said rod, and a valve rod and 10 float guiding yoke connected to said valve casing and bodily removable therewith.
8. In an air lift booster, a booster casing, inlet and discharge pipes therein, and means 15 effective to maintain a substantially constant liquid level in said booster consisting of a relief valve, a rod connected therewith, a float carried on said rod, a valve casing forming a guide for said valve, and means 20 attached to the booster casing and extending from the top thereof to a point above the bottom thereof and beyond the float and forming a guide for the opposite end of the rod.
9. In an air lift booster for maintaining 25 a constant flow of liquid, a booster casing having inlet and discharge pipes therein, a pressure regulating valve governed by the effects of pressure variation in said booster 30 and operating *per se* to control said booster and maintain a substantially constant liquid level therein, a float connected to said valve and movable therewith, and valve and float guiding means carried by the top of the 35 booster casing.
10. In an air lift booster, a booster casing having inlet and discharge pipes therein, a relief valve, a diving bell float connected to said valve, and means for preventing 40 surging in said float.
11. In an air lift booster, a booster casing having inlet and discharge pipes therein and an opening in its top, a relief valve, a diving bell float connected thereto, and 45 means for preventing surging in said float removable through the opening in said casing.
12. In an air lift booster, a booster casing having inlet and discharge pipes therein, a relief valve, a valve rod connected thereto, a float carried on said valve rod, guiding means for said rod, and means disposed adjacent said float for preventing surging therein. 50
13. In an air lift booster, a booster casing having inlet and discharge pipes therein, a relief valve, a valve rod connected thereto, a float carried on said valve rod, a yoke carried by said casing in which said rod and float are reciprocable, and means 55 carried by said yoke for preventing surging in said float.
14. In an air lift booster, a booster casing having inlet and discharge pipes therein, a relief valve, a valve rod connected thereto, a diving bell float carried on said valve rod, a yoke carried by said casing through which said rod is reciprocable, and a plate carried by said yoke and disposed adjacent the mouth of said float. 60 70
15. In an air lift booster, a booster casing having inlet and discharge pipes therein, a valve casing disposed over an opening in said booster casing, a valve movable in said casing, a rod connected to said valve 75 and extending into said booster casing, a float carried on said rod, a valve rod and float guiding yoke connected to said valve casing and bodily removable therewith, and a plate carried by said yoke and disposed adjacent the mouth of said float. 80
16. In an air lift booster, a booster casing, inlet and discharge pipes therein, a relief valve, a rod connected therewith, a float carried on said rod, a valve casing forming 85 a guide for said valve, means attached to the booster casing and extending from the top thereof to a point above the bottom thereof and beyond the float forming a 90 guide for the opposite end of the rod, and means carried by said last mentioned means for overcoming surging in said float.

In testimony whereof I affix my signature.

HALBERT B. HALVORSEN.
